UNITED STATES PATENT OFFICE

136,818

DESIGN FOR A WIRE CLAMPING TOOL

Lewis T. Paulson, Excelsior, Wis.

Application August 16, 1943, Serial No. 110,927

Term of patent 3½ years

To all whom it may concern:

Be it known that I, Lewis T. Paulson, a citizen of the United States, residing at Excelsior, in the county of Richland and State of Wisconsin, have invented a new, original, and ornamental Design for a Wire Clamping Tool, of which the following is a specification, reference being had to the accompanying drawing, forming part thereof.

Figure 1 is a side elevational view of a wire clamping tool showing my new design,

Figure 2 is an elevational view of the opposite side thereof,

Figure 3 is a top plan view, and

Figure 4 is an end elevational view thereof.

I claim:

The ornamental design for a wire clamping tool, as shown.

LEWIS T. PAULSON.
